MELVIN L. SEVERY, OF ARLINGTON HEIGHTS, MASSACHUSETTS, ASSIGNOR TO SEVERY MANUFACTURING COMPANY, OF BOSTON, MASSACHUSETTS, A CORPORATION OF MASSACHUSETTS.

FRICITION DRIVING MECHANISM.

1,135,628.

Specification of Letters Patent. Patented Apr. 13, 1915.

Application filed June 25, 1913. Serial No. 775,677.

To all whom it may concern:

Be it known that I, MELVIN L. SEVERY, of Arlington Heights, in the county of Middlesex and State of Massachusetts, have invented certain new and useful Improvements in Friction Driving Mechanism, of which the following is a specification.

This invention relates to an improvement in friction driving mechanism particularly adapted for use in automobiles, although not limited to such use.

The object of the invention is to provide a device of this character, having a driven member composed of a plurality of independently movable sections which are adapted to engage a driving member and be driven thereby in accordance with the speed of the particular portion of the driving element which they engage, without interference from portions of the driven element engaging other portions of the driving element, and without substantial slippage or drag between the driving and driven elements.

Heretofore, as usually constructed, the driving and driven elements have been each composed of single disks or integral rolls placed at right angles to one another. With such a construction, when the disks are in contact, the inner edge of the disk which has its periphery in contact with the flat face of the other disk travels over a portion of said flat face which is moving at a slower circumferential speed than that portion which is in contact with the outer edge of the periphery of said first mentioned disk. Consequently the first disk tends to rotate at a speed midway between the two extremes, so that the inner half of the width of its periphery is moving faster than the corresponding portion of the flat face of the other disk, thus causing slippage; and the outer half of the width of said periphery is moving slower than the corresponding portion of said flat face, thus causing said peripheral face to lag with respect to this portion of the flat face. Accordingly, the primary purpose of the invention is to overcome this objectionable feature. In the present embodiment of the invention the driven member is composed of a series of independently rotatable disks which are adapted to be brought into driving relation with the

driven shaft whenever their speed becomes equal to that of said shaft.

The invention will be readily understood from an inspection of the accompanying drawings, in which—

Figure 1 is an end elevation of the device showing a convenient means for varying the pressure between the disks, Fig. 2 is a front elevation of the same, Fig. 3 is a fragmentary central longitudinal section taken on the line 3—3 in Fig. 6, Fig. 4 is a fragmentary transverse vertical section taken on the line 4—4 in Fig. 3, showing the manner in which the disks coöperate with the driven shaft, Fig. 5 is a sectional end elevation of the driven disk, with one of its side plates broken away, Fig. 6 is a fragmentary transverse vertical section showing the roller clutches, Fig. 7 is a fragmentary section taken on the line 7—7 in Fig. 5, and Fig. 8 is a horizontal section taken on the line 8—8 in Fig. 1, showing the shaft and bearings in elevation.

As illustrated in the drawings, the present embodiment of the invention comprises a driving shaft 10 and a driven shaft 12. A driving disk 14 is connected to the shaft 10 by a universal joint 16, and is preferably made hollow and filled with some sound-deadening material 18, such as sand or any other suitable material. The driving face of the disk 14 is preferably substantially flat, while the rear face is provided with an annular conical flange 20, which is adapted to engage either of two idlers 22, 24, mounted on shafts journaled in suitable bearings 26, on a frame 28, said disk engaging one idler or the other according as the driven member is at one side or the other of the driving disk 14. The crowding friction between the driving and driven members is taken by these idlers.

The driven shaft 12 may be journaled in eccentrics 30, rotatably mounted in bearings 32 on the frame 28. The eccentrics 30 are provided with arms 34, which are connected by links 36 with a lever 38, whereby by moving said lever the eccentrics 30 are partially rotated to vary the position of the center of the shaft 12, and consequently the periphery of the driven element with respect to the face of the driving disk, thereby varying the pressure exerted between these

driving and driven elements. It is obvious that the driving element 14 might be moved toward the driven element 12, instead of vice versa. During the rotation of the parts the centrifugal action of the disk 14 tends to place this disk at right angles to its shaft 10 and accordingly exert a pressure upon the driven member, said disk 14 being tilted out of its right angled position by the pressure of the driven element as clearly shown in Fig. 8. This pressure obviously would be increased by any increase in the speed of the disk.

The driven element comprises a plurality of independently rotatable annular plates 40, 41, 42, 43, 44, 45, rotatable about a sleeve 47, which is slidably keyed to the driven shaft 12, and each surrounded by a ring 40^a, 41^a, 42^a, 43^a, 44^a, 45^a, separated therefrom by a space 46 in which a corrugated spring 48 is mounted. These springs are held in place by thin rings 50, 52, secured to the opposite sides of the plates 40—45 and let into annular recesses formed in the faces of said plates so that the outer faces of said plates and rings 50, 52 are flush. The rings 50, 52 are also let into the sides of the rings 40^a—45^a, but with clearance all around the peripheries of the former, so that the rings 40^a—45^a may slide between their respective pairs of rings 50, 52, when the springs 48 yield. The rings 40^a—45^a may be held from circumferential movement with respect to the plates 40—45, respectively, by pins 54, which may be fast in said plates and loose in said rings, as shown in Fig. 7. The rings 40^a—45^a are provided preferably with steel, aluminum, fiber or other tires or rims 56 affixed thereto in any desired manner and adapted to engage the flat face of the disk 14, said driven elements, or composite disks as they may be termed, being adapted yieldingly and independently to engage said flat face and make a good driving contact therewith.

The sleeve 47, in the present instance, is provided with four recesses 60, 61, 62, 63 in its periphery, and each recess is formed with a radial wall 64 and a wall 66 at right angles thereto, the latter being formed with a series of channels 68 in which balls or rollers 40^b, 41^b, 42^b, 43^b, 44^b, 45^b, are guided. The two walls of the recesses 60, 61, 62, 63, respectively, together with the inner peripheries of the plates 40—45 form substantially triangular passages of ball or roller clutches, said rollers acting to connect said plates in driving relation with the sleeve 47, and consequently with the driven shaft 12, when said rollers are crowded between the grooved walls 66 and the internal peripheries of the plates 40—45. It will be noted by reference to Fig. 6 that the two recesses 60, 62 open in one direction so as to clutch the rollers when the plates are rotating in the direction indi-

cated by the arrow, and at sufficient speed, whereas the recesses 61 and 63 open in the opposite direction, and in these latter recesses the rollers are not in driving relation. Thus one pair of recesses is active when the plates 40—45 are rotated in one direction, and the other pair of recesses are active when said plates are rotating in the opposite direction.

The rollers are normally pressed into engaging or clutching position by springs 70, which are housed in recesses 72 formed in the sleeve 47, but the inactive sets of rollers are adapted to be pressed back out of engaging position by rocker bars 74 carried by arms 76 fast on rocker shafts 78, the latter being journaled in the end plates 80, 82, which are affixed to the ends of the sleeve 47. A finger 84 projects inwardly from each shaft 78 and is connected to one end of a coiled spring 86, the other end of which is connected to the sleeve 47. These springs tend normally to swing the rocker bars 74 away from the rollers 40^b—45^b, so that the latter are free to be crowded into clutching position, as will be hereinafter explained.

The shaft 12 is provided with four longitudinally extending cams 90, 91, 92, 93, the cams 90, 92 extending from near one end of said shaft past its middle, and the cams 91, 93 extending from near the other end of said shaft past its middle. These cams are deflected slightly at their inner ends to facilitate the gradual engagement and movement of the fingers 84 thereby when the sleeve 47 is moved longitudinally by means of a shipper 94, which engages a grooved collar 96 forming a part of the plate 80. When the driven element is in the position shown in Fig. 8 the cams 90 and 92 are out of action and the fingers 84, 84^b (see Fig. 6) are free to be swung by their springs 86 to cause the rocker-bars 74, 74^b to release the rollers in contact therewith, so that they may be forced by their respective springs 70 into position ready to be clutched by the plates 40—45.

The clutching action is brought about as follows: Take for example the composite disk 40, which, as shown, engages the driving disk 14 at the greatest distance from the center of the latter; consequently the former is rotated at the greatest speed of any of the driven members. The rotation of the plate 40 around the sleeve 47 causes said plate to force the rollers 40^b and 40^a outward along the grooved surfaces 66, thereby clutching said plate into driving relation with said sleeve, so that they both rotate at the same speed. If the plate 41 is rotating slower than the plate 40, it will not clutch the roller 41^b and the roller in its set corresponding to the roller 40^a, but as soon as the speed of said plate 41 picks up sufficiently it will clutch its rollers and move them from the 120

dotted line position shown in Fig. 4 to the full line position shown in said figure. Thus each composite disk will be brought into driving relation with the sleeve 47 and the shaft 12 according as the speed of the former becomes sufficiently great to overtake its rollers and clutch them, and prior to that time it will impose no counter friction upon the faster moving members.

10 In the present embodiment of the invention it has been deemed desirable to have the driven member inactive, as it passes across the central portion of the driving disk, when the direction of rotation of the driven shaft is being reversed. By reference to Fig. 8 it will be seen that the cams 90, 91, 92, and 93 overlap for a short distance along the middle of the shaft 12. When the sleeve 47 is in this position, the 20 cams 90-93 are all active and the fingers 84, 84^a, 84^b, and 84^c are engaged to swing their respective rocker bars 74, 74^a, 74^b, and 74^c so that the rollers co-operating therewith are moved inward into disengaging position, 25 thus allowing the composite disks 40-45 to rotate idly about the sleeve 47. Then when the sleeve and disks are moved to the right hand end of the shaft 12, the cams 91 and 93 go out of action, thus freeing the fingers 84^a and 84^c and allowing them to be swung by their springs 86 to release the rollers in contact with the rocker-bars 74^a and 74^c, so that these rollers can be forced into clutching 30 position by their respective disks when 35 the speed of the latter is sufficient, as heretofore explained.

I do not restrict myself to the particular embodiment of the invention chosen for illustration as obviously the advantages of 40 the invention may be secured in greater or less degree in modified forms of the device. For example the laminated construction of the friction roller will give its characteristic advantages in various types of 45 variable speed friction gears beside the flat disk type illustrated. The structure of the friction roller is also subject to variation and while I prefer a ball clutch mechanism, other equivalent intermittent grip devices 50 familiar to the mechanic may be substituted. I therefore use in certain of the claims the term "intermittent grip connections" in its broad sense to denote any device locking against motion in one direction while permitting substantially free motion in the opposite direction. Obviously either of the 55 friction elements may be the driver and the other be driven thereby.

What I claim is:—

60 1. A friction driving mechanism comprising in combination a rotary friction element; a shaft; a second friction element composed of a plurality of independently rotatable sections mounted on said shaft and adapted frictionally to engage said first

named friction element; and means for automatically putting said sections into and out of driving relation with said shaft.

2. A friction driving mechanism comprising in combination a rotary friction element; 70 a shaft; a second friction element composed of a plurality of independently rotatable sections mounted on said shaft and adapted frictionally to engage said first named friction element; and means controlled by the speed of any section for placing said section in driving relation with said shaft.

3. A friction driving mechanism, comprising rotary driving means, a driven shaft, and a driven member composed of independently rotatable sections adapted to be brought into driving relation with said driven shaft.

4. A friction driving mechanism, comprising rotary driving means, a driven shaft, 85 and a driven member composed of independently rotatable sections adapted to be brought into driving relation with said driving means and adapted to be automatically brought into driving relation with 90 said shaft when their speed is sufficient.

5. A friction driving mechanism comprising in combination a rotary friction element; a shaft; a second friction element composed of a plurality of independently 95 rotatable sections mounted on said shaft and adapted frictionally to engage said first named friction element; and rolling clutch members interposed between each of said sections and said shaft.

6. A friction driving mechanism, comprising a rotary friction element, a shaft, a sleeve on said shaft provided with a plurality of recesses, a plurality of independently rotatable members surrounding said sleeve 105 and in frictional engagement with said friction element, and a plurality of rolling members in said recesses adapted to engage said rotatable members and bring them into driving relation with said sleeve when the 110 speed of said rotatable members is sufficient.

7. A friction driving mechanism, comprising a rotatable member having a plurality of recesses in its outer surface, one or more annular members surrounding said rotatable 115 member, a plurality of rolling members adapted to clutch said rotatable member to said annular member or members, means for moving said rolling member into clutching position, and means whereby said rolling 120 member may be withdrawn from clutching position.

8. A friction driving mechanism, comprising a pair of angularly disposed rotatable members, one of said members being yielding and arranged to assume various degrees of angularity, and means for moving the other of said members to vary the pressure between said elements.

9. A friction driving mechanism comprising 130

- ing a rotary disk, a pair of members concentrically arranged with a space therebetween, the outer of said members being adapted to coöperate with said disk, resilient means in said space, and means for varying the pressure between said disk and members.
10. A friction driving mechanism, comprising a rotary disk filled with sound deadening material, a second disk arranged at an angle to and coöperating with said first mentioned disk, and means for varying the pressure between said disks.
11. A friction driving mechanism, comprising a rotary friction element, and a co-acting composite friction element the parts of which operate independently of each other.
12. A friction driving mechanism, comprising a rotary friction element, a second friction element coating therewith and composed of independently rotatable sections adapted to be brought into driving action, means for moving said second friction element across the center of said first named friction element, and means for rendering said sections inactive when the center is crossed.
13. A friction driving mechanism comprising in combination a rotatable shaft; a friction element; pivotal connections between said shaft and friction element for constraining said friction element to rotate with said shaft while permitting relative swinging thereof about axes transverse to the axis of the shaft; and a rotatably mounted second friction element frictionally engaging said first friction element.
14. A rotary friction element comprising in combination a plurality of independently rotatable sections; intermittent grip connections for clutching said sections to a shaft; and means for reversing the direction of clutching of said connections to permit reverse directions of drive.
15. A friction driving mechanism, comprising a driving and a driven element each mounted upon a shaft, means for bringing said elements into operative relation, one of said elements being composed of independently rotatable sections, and means whereby said sections are put into or out of driving relation with their shaft.
16. A friction driving mechanism, comprising a driving and a driven element each mounted upon a shaft, means for bringing said elements into operative relation, one of said elements being composed of independently rotatable sections, and means

whereby said sections are automatically put into or out of driving relation with their shaft.

17. A change speed friction driving mechanism comprising in combination a rotary element having a friction surface which is a surface of rotation; and a friction roller axially movable to vary the radius of its contact with the friction surface of said rotary element and including a hub portion, a plurality of juxtaposed, unconnected annular tire portions rotatably mounted thereon, and intermittent grip connections between said hub and said tire portions.

18. A change speed friction driving mechanism comprising in combination a rotary element having a friction surface which is a surface of rotation; a friction roller axially movable to vary the radius of its contact with the friction surface of said rotary element and including a hub portion, a plurality of juxtaposed, unconnected annular tire portions rotatably mounted thereon, and oppositely acting intermittent grip connections between said hub and each of said tire portions; and a hold-out device for alternately rendering either of said intermittent grip connections inoperative, whereby said tire portions may be rendered freely rotatable with respect to said hub in one or the other direction.

19. A change speed friction driving mechanism comprising in combination a rotary element having a friction surface which is a surface of rotation; a friction roller axially movable to vary the radius of its contact with the friction surface of said rotary element and including a hub portion, a plurality of juxtaposed, unconnected annular tire portions rotatably mounted thereon, and oppositely acting intermittent grip connections between said hub and each of said tire portions; means for axially shifting said friction roller; and a hold-out device actuated by the axial shifting of said roller and adapted to render said intermittent grip connections alternately inoperative, whereby said tire portions are freely rotatable in respectively opposite directions with reference to said hub, in different respective axial positions of said roller.

In testimony whereof I have affixed my signature in the presence of two witnesses.
